(57) **CLAIM**

The ornamental design for a photo image scanner, as shown and described.

DESCRIPTION

FIG. 1 is a top, front and side perspective view of a photo image scanner, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the right of FIG. 2; and,

FIG. 7 is a side elevational view thereof from the left of FIG. 2.

The display portion of the photo image scanner in broken lines is shown for illustrative purposes only and forms no part of the claimed design.
